UNITED STATES PATENT OFFICE.

FRANK SWALES, OF NEW YORK, N. Y., ASSIGNOR TO SWALES SPECIALTY CO. INC., OF NEW YORK, N. Y., A CORPORATION OF NEW YORK.

BIT ATTACHMENT.

1,291,243.

Specification of Letters Patent. Patented Jan. 14, 1919.

Application filed May 24, 1918. Serial No. 236,261.

To all whom it may concern:

Be it known that I, FRANK SWALES, a subject of the King of Great Britain, residing in the borough of Manhattan, city, county, 5 and State of New York, have invented an Improvement in Bit Attachments, of which the following is a specification.

This invention relates to an attachment adapted to be applied to a bit, particularly 10 for a bit used in mousing, breaking, riding and driving horses, irrespective of the breed of the animal, and the purposes for which he is employed. The attachment comprising my present invention is adapted to be 15 fitted over the divided central portion of a bit and serves the double purpose of preventing the bit in the use thereof from injuring the tongue of the horse, and also for keeping the horse from getting his tongue 20 over the bit, and preventing him from running away. In carrying out the invention the article is preferably made of rubber or some other equally pliable and resilient material, and is adapted to be fitted over the 25 central divided portion of the bit with a member extending within the horse's mouth and lying over his tongue, for the purposes hereinbefore indicated.

The construction of the bit attachment 30 will be hereinafter more particularly described in conjunction with the accompanying drawing in which:

Figure 1 is a plan view of the attachment shown in extended position.

Fig. 2 is a side elevation of the same, and

Fig. 3 is a perspective view illustrating the use of the attachment.

As hereinbefore stated, the attachment comprising my present invention is preferably made of rubber, but as will be understood, may be made of any suitable and equally yielding or resilient material. This is so molded as to comprise a central cylindrical portion 10 divided longitudinally 45 and having extending from one side thereof an enveloping apron 11. At the extremity of the apron there is a looped member 12. In the apron adjacent the cylindrical section there is an opening 13, and the adjacent 50 edge along which the cylindrical section is broken is preferably recessed as indicated at 14. There is an open space between the end of the enveloping apron proper and the loop 12 as indicated at 15. 55 Extending in the opposite direction from

the broken cylindrical section 10 is a tongue member 16 in which in its upper surface adjacent the cylindrical section there is a transverse recess indicated at 17.

The parts of the divided bit are indicated 60 in Fig. 3 at 18 and 19 respectively, and these are connected, as is customary in bits of this type, by the ring joint indicated at 20. In the use of the hereinbefore described bit attachment the broken cylindrical section 65 is fitted over the central part of the members 18 and 19 of the bit so that the ring joint connecting the parts of the bit extend into and lie within the opening 13, and bear against the recessed portion of the edge of 70 the cylindrical section indicated at 14. The enveloping apron 11 is then passed around the cylindrical section 10 and the tongue 16 passed through the opening 15 so that the loop 12 lies within the transverse recess 75 17 with the parts in the position as shown in Fig. 3 and in dotted lines in Fig. 2. In use as will now be understood, the cylindrical section 10 with the apron enveloping the same, protects the horse's tongue in the use 80 of the bit, and the tongue 16 lying at the rear of the bit, and extending over the horse's tongue, prevents the horse from raising his tongue sufficiently far to pass it over the top of the bit. As will be readily 85 understood, the bit attachment is maintained in position on the bit, that is, is prevented from sliding toward either side by the divided portion of the bit extending through the opening 13 in the enveloping apron 11. 90

I claim as my invention:

1. A bit attachment comprising a cylindrical portion adapted to surround the central portion of a bit, an enveloping apron extending from the cylindrical portion and 95 means also associated with the cylindrical portion for maintaining the apron in position when surrounding the cylindrical portion.

2. A bit attachment comprising a cylindrical portion adapted to surround the central part of a bit, an enveloping apron extending from the cylindrical portion, means for preventing the horse from putting his tongue over the bit, and means associated 100 105 with the last aforesaid means for maintaining the apron in position when enveloping the cylindrical portion.

3. A bit attachment comprising a divided cylindrical portion adapted to surround the 110

central part of a bit, an enveloping apron extending from one side of the cylindrical portion, a loop at the extremity of the apron, and means associated with the cylindrical portion adapted to be engaged by the loop to maintain the said apron in position in enveloping the cylindrical portion.

4. A bit attachment comprising a divided cylindrical portion adapted to surround the central part of the bit, an enveloping apron

extending from one side of the cylindrical portion, a loop at the extremity of the apron, and a tongue extending from the other side of the cylindrical portion and having in one surface thereof adjacent the cylindrical portion a recess adapted to receive the said loop for maintaining the apron in position when enveloping the said cylindrical portion.

Signed by me this 22nd day of May, 1918.

FRANK SWALES.
